FIG. 4.

FIG. 5.

Stephen A. Gregory,
INVENTOR

BY *Victor J. Evans*

ATTORNEY

UNITED STATES PATENT OFFICE

STEPHEN A. GREGORY, OF STAMFORD, CONNECTICUT

ARTICLE HOLDER

Application filed July 16, 1928. Serial No. 293,102.

This invention relates to a holder for articles of various kinds, the general object of the invention being to provide a member formed of resilient material and having a substantially pear-shaped opening therein through which the handle of a broom or other article is adapted to be passed, with means for hingedly connecting the member to a wall or the like so that when the member assumes an inclined position, due to the action of gravity, the handle of the article will be gripped by opposing walls of the opening of the member and thus be supported by the member.

This invention also consists in certain other features of construction and in the combination and arrangement of the several parts, to be hereinafter fully described, illustrated in the accompanying drawing and specifically pointed out in the appended claims.

In describing my invention in detail, reference will be had to the accompanying drawing wherein like characters denote like or corresponding parts throughout the several views, and in which:

Figure 1 is a front view of the device.

Figure 2 is a view showing the device in use.

Figure 3 is a sectional view through the device.

Figure 4 is a section on line 4—4 of Figure 3.

Figure 5 is a section on line 5—5 of Figure 3.

In these views, the numeral 1 indicates the holder which is formed of rubber or the like and which has one end of substantially V-shape and its other end of substantially semi-circular shape so as to form an opening of substantially pear shape, with one portion of the opening of V-shape, as shown at 2, and the other portion of semi-circular shape, as shown at 3. The member is of circular shape in cross section as shown, and a staple 6 has its diverging prongs embedded in the V-shaped part of the member with its eye part extending from the point of the member, as clearly shown in Figures 1, 2 and 3. The eye of the staple passes through the eye of an eye bolt or pin 7 so that the member 1 can be hingedly connected with a wall or other support, as shown in Figure 2.

When the handle A of a broom or other object is passed through the opening in the member, the member will assume an inclined position under the action of gravity, as shown in Figure 2, so that the V-shaped walls 2 of the opening will grip a portion of the handle at one side thereof and the rounded walls 3 of the opening will grip the front part of the handle, as shown in Figure 2, and thus the article will be firmly supported by the member.

It is thought from the foregoing description that the advantages and novel features of my invention will be readily apparent.

It is to be understood that I may make changes in the construction and in the combination and arrangement of the several parts, provided that such changes fall within the scope of the appended claims.

What I claim is:

1. A device of the class described comprising a member formed of resilient material having an opening therein formed with an upper V-shaped part and a semi-circular lower part for receiving a handle of an object to be supported, an eye carrying member having a portion embedded in the member and a wall engaging member having an eye which engages the eye of the first member.

2. A device of the class described comprising a member formed of resilient material having an opening therein formed with an upper V-shaped part and a semi-circular lower part for receiving a handle of an object to be supported, said member being endless and means whereby the upper end of the member can be attached to a wall.

In testimony whereof I affix my signature.

STEPHEN A. GREGORY.
